APPARATUS FOR CLEANING GRAIN AND
DESTROYING THE INSECT LIFE THEREIN

Franklin S. Smith, North Haven, Conn.

Application September 7, 1949, Serial No. 114,431

11 Claims. (Cl. 21—91)

1

This invention relates to apparatus for treating grain, that is, the kernels of the various cereals.

Briefly, the machine includes a spout, generally indicated at 10. Grain flowing downwardly through spout 10 enters a funnel-shaped injector conduit, generally indicated at 12, into an air stream generated by a centrifugal constant pressure blower 14. The air stream accelerates the grain downwardly through conduit 16 onto a conoidal member, generally indicated at 18. The outer portions of conoidal member 18 and the inner surface of conoidal shell 20 form a converging-diverging nozzle 19 which accelerates and directs the grain and air stream in a general radial direction against a target array in the form of a simple labyrinth, generally indicated at 24 (Figures 1 and 4), positioned outwardly therefrom. The target array consists of a plurality of vertically-positioned cylindrically shaped targets presenting elastomer surfaces such as rubber of about 50 durometer hardness. The grain impacts the targets of the target array with sufficient intensity to cause lethal shocks which destroy the life of insect infestation of the grain and also to separate the dirt from the grain, particularly the dirt in crevices in the grain such as the dirt in the crease in a grain of wheat.

The majority of the kernels strike the targets 24 without hitting the screen 28 and fall downwardly in the machine through its funnel-shaped lower portion and thence into conduit 26. Dirt and other foreign particles are carried between the targets of the array by the air stream and thence through a screen, generally indicated at 28 (Figures 1, 4 and 5) into passageways 30 and 32. The air stream flows in passageways 30 and 32 from the left to the right, as viewed in Figure 4, and thence into a pair of cyclone dust collectors 34 and 36 (Figure 2). The dirt is separated from the air stream in the dust collectors and the air stream passes upwardly through conduit 38 to inlet of blower 14 and is circulated through the machine. The dirt and other foreign material pass downwardly in the cyclone collector and are discharged from a hopper 40 by a conventional air lock valve 42 which is driven by a motor (not shown).

One of the objects is to provide an apparatus capable of fine cleaning, to be employed after the customary grain screening and cleaning which separates the relatively coarse foreign materials from the grain stream. Another object is to provide apparatus of the above character which

2

will be simple, practical and thoroughly durable. Another object is to provide a new and improved apparatus of the above character for simultaneously destroying the life of insect infestation and fine cleaning of the grain. Another object is to provide apparatus of the above character capable of destroying the life of insect infestation without shattering sound kernels. Another object is the inclusion of means within apparatus of the above character for effecting a separation of dust, crease dirt, small insects, insect particles and small foreign particles from the grain. Other objects will be in part obvious and in part pointed out hereinafter.

15 The invention accordingly consists in the features of construction, combinations of elements and arrangement of parts, all as will be illustratively described herein and the scope of the application of which will be indicated in the following claims.

In the accompanying drawings, in which is shown one of the various possible embodiments of this invention,

20 Figure 1 is a side elevation of the machine with certain parts in section and others broken away for purposes of illustration;

25 Figure 2 is a side elevation of the cyclone dust collectors taken from the line 2—2 of Figure 1; Figure 3 is a plan of the machine shown in

30 Figure 1; Figure 4 is a horizontal section taken on the line 4—4 of Figure 1;

35 Figure 5 is a vertical section on an enlarged scale taken on the line 5—5 of Figure 3;

Figure 6 is a plan on an enlarged scale of the lower ends of a series of the targets taken from the direction of the arrows 6 in Figure 1;

40 Figure 7 is a side elevation on an enlarged scale of a single target, certain parts being broken away for purposes of illustration;

Figure 8 is a side elevation of a portion of the conduit leading to grain inlet of apparatus, certain portions of this figure being vertically sectioned; and

45 Figure 9 is a side elevation partly in section and partly in elevation of a portion of the conduit through which grain passes from the machine.

Similar reference characters refer to similar parts throughout the several views of the drawings.

Referring now to Figure 1, the machine is supported by four legs, 43, 44, 45 and 46. All of the legs are similar in construction to leg 44 (Figures 1, 3 and 5) and include sections 48 and

50 (Figure 5). These sections coact to support the funnel-shaped casting, generally indicated at 52 (Figures 1 and 5), and a ring-shaped casting 54 (Figures 1, 3 and 5), which form the framework of the machine. The lower portion of leg section 50 (Figure 5) extends into the hollow interior of section 48 and is pinned thereto by a pin 56. Section 50 extends through a hole 58 in casting 52, and casting 52 rests upon the upper end of section 48. A plug 60 is mounted in the upper end of section 50 and is pinned thereto by a pin 62. Plug 60 extends through a hole 64 in casting 54, and casting 54 rests upon the upper end of section 50. Casting 54 is held against the upper end of section 50 by means of a nut 66 threaded on the upper end of plug 60. The four legs thus support castings 52 and 54 in spaced relationship with respect to each other to form a framework for the machine.

The targets in the target array are mounted on shell 20. The outer edge of shell 20 (Figures 1 and 5) includes an outwardly extending annular flange 20a which extends over an inwardly extending flange 54a on casting 54. Thus, casting 54 supports shell 20 with respect to the machine. Shell 20 includes a horizontal target supporting section 20b of circular shape on which the targets are mounted. Each target consists of a rod 70 (Figure 7) having its upper end threaded and having an elastomer cover 72 molded thereon. The elastomer surfaced targets are of a hardness which does not shatter the sound kernels upon impact; however such kernels that have been reduced to mere shells due to insect feeding upon the endosperm and/or germ are shattered. The powdered interiors are carried by the air stream through the screen. The targets 72 are arranged in two circles in the form of a simple labyrinth, the targets in the circles being in staggered relationship with respect to each other so that each target covers the space between a pair of targets in the other circle of targets (Figure 6). The rod 70 (Figure 5) of each target 72 extends through a vertical hole in section 20b of shell 20 (Figure 5) and is secured to section 20b by means of a nut, such as nut 74.

Conoidal member 18, which, as pointed out hereinabove, forms a nozzle 19 in conjunction with shell 20 to direct the stream of grain against the targets, is supported by three supporting rods, two of which are shown in Figure 1. These rods 76 have their upper ends positioned in sockets such as socket 78 in conoidal member 18 and their lower ends extend into sockets, such as socket 80, formed in casting 52. These rods rigidly support the conoidal member so that it forms a circular nozzle 22 which directs the air stream and grain against the target array at an angle slightly downwardly from the horizontal.

After the air stream and grain strike the targets 72, the dirt and other foreign material is shaken loose from the grain and is carried by the air stream outwardly through a cylindrically-shaped screen 28 (Figures 1, 4 and 5). Screen 28 has a plurality of horizontal slots 84, the width of which is smaller than the type of grain being cleaned but is sufficiently large to permit dust, dirt, mites, and most insects infesting stored grain to pass therethrough. It might be well at this point to note that as heretofore pointed out, the apparatus herein described is primarily concerned with what has been termed "fine cleaning." In other words, this apparatus is installed in the millstream to receive grain which has gone

through preliminary screening and cleaning apparatuses which separates relatively coarse particles of dirt and foreign materials, such as bits of wood and iron, vermin excreta and other particles commonly found in raw grain fed into the millstream from storage. In other words, the grain which is treated by the present device is relatively clean, being adulterated by relatively fine particles of dirt, excreta or other material, and such small dirt or other particles adhering to the grain kernels or being lodged in the creases thereof. These particles of dirt and other foreign matter are almost invariably of considerably smaller size than the grain particles themselves, although there might well be present adult insects, although in small proportion, which are individually larger than the largest kernels. Less mature insect infestation might also be present, but would be in the egg, larvae or pupae stages. In any event, the apparatus is intended to separate from the grain only those entrained particles which are smaller than the grain kernels themselves, any larger particles passing along with the grain kernels into the millstream for subsequent treatment. Referring to Figure 5, it will be noted that the width of slots 84 gradually increases as each slot is followed outwardly toward passageways 30 and 32 (Figure 4). This prevents the slots from being clogged by dirt, as any particle which enters a slot is carried therethrough by the air stream. Screen 28 overlaps and is mounted on axially concentric cylindrically-shaped seats 86 and 88 formed on shell 20 and casting 52. The ends of screen 28 overlap and are held together by a series of screws, such as screw 90. The screen 28 has a sufficient slot area therein to prevent excessive air flow resistance. To dissipate the electric charge on the grain and the grain dust, a lug 57 connected to casting 52 by screw 59 is grounded by conductor 61 (Figure 5). To insure good electrical contact between screen 28 and casting 52, screen 28 is connected to casting 52 by screw 63.

Passageways 30 and 32 function as semi-volute channels (Figure 4), each gradually increasing in width and consequently in cross section from the splitter 94 to the outlet port 96. The outer wall of both passageways 30 and 32 is formed by a band 98 (Figure 5) which is clamped against a pair of seats 100 and 102 formed on castings 52 and 54. Seats 100 and 102 are cylindrical in shape but are eccentric with respect to seats 86 and 88 to make passageways 30 and 32 (Figure 4) increase in width as they are followed to the right, as viewed in Figure 4. The ends 98a and 98b of band 98 are connected to a casting of rectangular shape in vertical cross section, generally indicated at 104, which includes portions 104a and 104b which extend outwardly behind band 94 and which forms the outlet port for passageways 30 and 32. The ends 98a and 98b of band 98 are connected to casting 104 by cap screws 106 and 108, which, when tightened, draw the band 98 tightly against seats 100 and 102 (Figure 4). Thus, it will be seen that band 98 and screen 28 are easily removable so that the targets of the target array are readily accessible and the interior of the machine may be quickly cleaned.

To direct the air stream flowing through the left-hand portion of screen 28 (Figure 4) to the right passageways 30 and 32, splitter 94 is provided. Splitter 94 (Figure 1) extends from the top to the bottom of screen 28 and is secured along one vertical edge to band 98 by rivets 110. It will be noticed that the two sides of splitter 94

are curved to direct the air stream upwardly and downwardly, as viewed in Figure 4, into passageways 30 and 32. At the opposite ends of passageways 30 and 32 are a pair of vertically-positioned curved guiding plates 112 and 114. The upper and lower ends of these guiding plates are secured to casting 104 in any suitable manner (not shown) and they serve to direct the air stream flowing through passageways 30 and 32 outwardly through port 96. It will be noted that the right-hand ends of plates 112 and 114 are spaced with respect to each other. This permits the air stream flowing through the portion of screen 28 covered by guiding plates 112 and 114 to flow into the passageway 116 (Figure 4) through port 96. Thus, the air stream is guided through passageways 30 and 32 from the left to the right, as viewed in Figure 4, and the passageways gradually increase in cross-sectional area to permit the air stream to flow through the screen 28 evenly from all directions.

The air stream and foreign material passing from port 96 (Figure 4) enters passageway 116 (Figure 1) which is connected to the intake ports of a pair of cyclone dust collectors 34 and 36. The dirt and other foreign material is separated from the air stream in the cyclone dust collectors, the dirt passing downwardly through the lower ends of the cyclone collectors into hopper 40 (Figures 1 and 2) and is discharged from hopper 40 by means of air lock valve 42 driven by a motor (not shown). The air stream from each dust collector passes upwardly through conduits 120 and 122 into a conduit 124 connected to the intake port of blower 14. Blower 14 is driven by a motor 126 and generates an air stream which flows through conduit 130 into a volute casing 132. Volute casing 132 in conjunction with injector conduit 12 serves to distribute the air stream evenly into conduit 16 so that the grain passing from the lower end of spout 10 is accelerated downwardly and uniformly into nozzle 19.

If spout 10 is relatively short and to prevent the air stream from flowing upwardly through spout 10 (Figure 1) when no grain is flowing down it, spout 10 may include a series of funnel-shaped sections, such as sections 146 and 148 (Figure 8). The purpose of sections 146 and 148 is to cause abrupt air expansions as the air moves upwardly with consequent loss in total pressure and thus impede upward flow of air. These sections do not appreciably interfere with the downwardly flow of grain. A series of sections 140, 142 and 144 (Figure 9) are also provided in conduit 26 for a similar purpose.

In operation, the high velocity air stream generated by constant pressure blower 14 flows through conduit 130 and volute casing 132 and thence through injector conduit 12. The low velocity grain stream, which is the grain and its entrained air, flows downwardly through spout 10 into injector conduit 12 within which the two streams become confluent. The air stream accelerates the grain stream through conduit 16 and conoidal nozzle 19 and from nozzle outlet 22. The kernels pass outwardly from nozzle 19 in a general radial direction and strike targets 72. A majority of the kernels pass downwardly through the funnel-shaped lower portion of the machine into conduit 26. Some kernels carom between the targets to the screen, where again they fall downwardly into the lower portion of the machine and thus into conduit 26 as they cannot pass through screen 28. As pointed out hereinabove, the targets are so spaced with respect to

each other that every kernel of grain strikes a target which loosens the dirt thereon, the impact also killing any insect life.

The dirt and other foreign material passes outwardly through the slots 84 in screen 28 into passageways 30 and 32 (Figure 4). The splitter 94 directs the air stream passing through the left-hand side of the screen, as viewed in Figure 4, upwardly and downwardly. Because the passageways 30 and 32 gradually increase in cross sectional area throughout their lengths, they accommodate the air stream passing through screen 28 so that it flows substantially uniformly therethrough.

The air stream is guided by guiding plates 112 and 114 into the intake conduit 116 leading to cyclone dust collectors 34 and 36. The cyclone dust collectors separate the foreign material from the air stream (Figures 1 and 2), the air stream passing upwardly through conduits 120 and 122, and the foreign material passing downwardly into hopper 40. The air stream passing upwardly through conduits 120 and 122 feeds blower 14, which circulates the air through the machine. The dirt and foreign material with its entrained air are discharged from the machine by means of an air lock valve 42.

By directing the grain against targets of the type described, no shattering of sound kernels takes place. The grain is simply subjected to a shock sufficient to remove all dirt therefrom, including the crease dirt and the shock also destroys the insect life of infestation of the grain. The targets accomplish this because they are surfaced with an elastomer which is not deformed beyond its elastic limit and which absorbs a sufficient amount of the shock to prevent fracture of sound kernels and also because the targets do not have any edges.

It will be seen that practical and efficient apparatus has been described for cleaning grain and destroying the insect life therein. The velocity with which the grain strikes the targets may be on the order of 200 feet per second as a maximum upon impact and is readily controlled by varying the speed of the blower. Furthermore, the targets are so constructed and positioned that all kernels of grain are subjected to shock which separates the dirt from the kernels but does not shatter them. It will thus be seen that the several objects hereinabove mentioned, as well as many others, have been successfully accomplished.

As many possible embodiments may be made of the above invention, all without departing from the scope of the invention, it is to be understood that all matter hereinabove set forth or shown in the accompanying drawings is to be interpreted as illustrative and not in a limiting sense.

What is claimed is:

1. In apparatus of the type described, in combination, a conduit, a blower for forcing a high velocity stream of air through said conduit, means for introducing the product being treated into said stream of air, a substantially annular shaped target array including a plurality of vertically positioned targets, and means to direct the stream of air and said product against said target array so that the individual particles of the product strike the vertical targets.

2. In apparatus of the type described, in combination, a conduit, blower for forcing a high velocity stream of air through said conduit, means for introducing the product being treated

into said stream of air, an elastomer surfaced target, means to direct the stream of air and said product against said target, and a screen located adjacent said target through which most of said air stream passes after carrying the product being treated against said target, the openings in said screen being of smaller size than the size of the particles comprising the product being treated, said air stream carrying dirt and other foreign material particles of a size smaller than said product particles through said screen.

3. In apparatus of the type described, in combination, a conduit, a blower for forcing a stream of air through said conduit, means for introducing the product particles being treated into said stream of air, a target array in the form of a simple labyrinth, means to direct the stream of air and entrained particles through said target array, said air stream carrying the product being treated against said targets, and screening means adjacent said target array through which most of said air stream passes after passing through said target array, said screening means having openings of smaller size than the size of the product particles being treated, said screening means separating the product being treated from particles of dirt and other foreign materials which are smaller than the product particles.

4. In apparatus of the type described, in combination, a conduit, a blower for forcing a high velocity stream of air through said conduit, means for introducing the product particles being treated into said stream of air, a substantially annular-shaped target array including a plurality of vertically positioned elastomer surfaced targets, a converging-diverging nozzle having a circular nozzle outlet positioned inwardly from said target array, means to direct the stream of air and said product through said nozzle against said target array, and means surrounding said target array for separating said air stream from the product being treated.

5. In apparatus of the type described, in combination, a conduit, a blower for forcing a stream of air through said conduit, means for introducing the product being treated into said stream of air, an annular-shaped target array including rows of vertically positioned targets, the targets in said rows being positioned in staggered and overlapping relationship with respect to each other, each target being substantially cylindrically-shaped and having an elastomer surface, and means for directing said air stream and the product being treated against said target array.

6. In apparatus of the type described, in combination, a conduit, means including a blower for forcing a high velocity stream of air through said conduit, a spout for introducing the product being treated into said conduit, a target array including a plurality of elastomer surfaced targets, a nozzle to direct the stream of air against said target array to carry the product being treated against said targets, screening means adjacent said target array through which most of said air stream passes after carrying the product being treated against said target array, the openings in said screen being smaller than the particles comprising the product being treated, said screening means separating the product particles being treated from particles of dirt and other foreign materials which are smaller than the product particles, said particles of dirt and for-

sign materials being carried through the screen by the air stream, and a hopper for collecting the product particles after treatment.

7. In apparatus of the type described, in combination, a conduit, a blower for forcing a stream of air through said conduit, a spout for introducing the product being treated into said conduit, an annular-shaped target array including a plurality of vertically positioned targets in staggered overlapping relationship with respect to each other, a converging-diverging nozzle disposed within said array and having a circular outlet for directing the air stream and the product being treated against said target array, and vertically-positioned screening means positioned outwardly from said target array to separate the product being treated from said air stream.

8. In apparatus of the type described, in combination, a conduit, a blower for forcing a stream of air through said conduit, means for introducing the product particles being treated into said stream of air, an annular-shaped target array including two rows of vertically positioned targets, the targets in said rows being positioned in staggered and overlapping relationship with respect to each other, each target being substantially cylindrically-shaped and having an elastomer surface, a nozzle positioned within said array and having a circular outlet for directing said air stream and the product particles being treated against said target array, a substantially cylindrically-shaped screen positioned outwardly from said target array, the openings in said screen being smaller than the size of the particles of the product being treated, and a hopper for receiving all particles that do not pass through said screen.

9. In apparatus of the type described, in combination, a conduit, a blower for forcing a stream of air through said conduit, a spout for introducing the product particles being treated into said stream of air, a conoidal member, the axis of said conoidal member being vertically positioned and aligned with the axis of the portion of said conduit positioned directly above said conoidal member, means coacting with said conoidal member to form a converging-diverging nozzle having a circular outlet opening at the lower edge of said conoidal member, a substantially annular-shaped target array in the form of a labyrinth including a plurality of elastomer surfaced targets positioned outwardly from said nozzle, said nozzle directing said stream of air and the entrained product against said target array, and means surrounding said array for separating said stream of air and particles of dirt and other foreign materials from the product being treated.

10. In apparatus of the type described, in combination, a conduit, a blower for forcing a stream of air through said conduit, a spout for introducing the product being treated into said stream of air, a conoidal member, the axis of said conoidal member being vertically positioned and aligned with the axis of the portion of said conduit positioned directly above said conoidal member, means coacting with said conoidal member to form a nozzle having a circular outlet opening at the lower edge of said conoidal member, a substantially annular-shaped target array including a plurality of elastomer surfaced targets having surfaces positioned outwardly from said nozzle, said nozzle directing said stream of air and the product being treated against said target array, and a substantially vertically positioned screen positioned outwardly from said target array, through which most of said air stream

passes, the holes in said screen being of smaller size than the size of the particles of the product being treated, whereby said screen separates the product being treated from said stream of air, and hopper means positioned beneath said screen for collecting the treated product.

11. In apparatus of the type described, in combination, a conduit, a blower for forcing a stream of air through said conduit, a spout for introducing the product being treated into said stream of air, an array of annular-shaped targets, said target array including a plurality of vertically positioned targets having elastic resilient exterior surfaces, a conoidal member for directing said stream of air and the product being treated outwardly against the inside of said target array, a vertically positioned annular-shaped screen surrounding said target array, the holes in said screen being of smaller size than the particles of the

product being treated, a passageway positioned outwardly from said screen, most of said air stream passing through said screen into said passageway and carrying particles of dirt and other foreign material capable of passing through said screen with it, a hopper for collecting the treated product, means connected to said passageway for separating said dirt and other foreign material from said air stream, and means connecting said last-mentioned means to said blower.
